UNITED STATES PATENT OFFICE

WILLIAM L. HUMMEL, OF CHICAGO, ILLINOIS.

REFRIGERATOR.

Application filed January 4, 1928. Serial No. 624,398.

To all whom it may concern:

Be it known that I, WILLIAM L. HUMMEL, a citizen of the United States, and a resident of Chicago, in the county of Cook and State of Illinois, have invented a new and useful Improvement in Refrigerators, of which the following is a full, clear, and exact description.

My invention relates to improvements in refrigerators, and it consists in the combinations, constructions, and arrangements herein described and claimed.

An object of my invention is to provide a means for stopping the circulation of the cooled air from the ice compartment of the refrigerator when the doors from the food compartments or the ice compartment is opened. My present invention is an improvement over the invention set forth in my prior Patent No. 1,404,961.

A further object of my invention is to provide an efficient means for stopping circulation of air in a refrigerator when the doors are open without the presence of levers or the like projecting up into the ice compartment or down into the food compartments thereby obstructing entrance to the compartment.

A further object of my invention is to provide a device of the type described that will function efficiently whether one or a plurality of the doors of the refrigerator are open.

A further object of my invention is to provide a device of the type described that is extremely simple in construction, that is positive in action, and is thoroughly practical commercially.

Other objects and advantages will appear in the following specification, and the novel features of the invention will be particularly pointed out in the appended claim.

My invention is illustrated in the accompanying drawings forming part of this application, in which

Figure 1 is a sectional view of an embodiment of my invention,

Figure 2 is a sectional view of a part of the mechanism illustrated in Figure 1, with one of the two doors closed, and

Figure 3 is a sectional view of the mechanism illustrated in Figure 2 with both of the doors closed.

In carrying out my invention I make use of the ordinary type of refrigerator having

walls 1, doors 2 and 3 arranged to admit ice and food to the ice and food compartments respectively, and a perforated floor 4 through which cooled air from the ice compartment above the floor 4 may flow to the food compartments below the floor 4. This perforated floor 4, (see Figure 1) has perforations 5 therethrough at equal distances from one another.

A shutter 6 having perforations 7 of the same caliber as the perforations 5 is slidably disposed immediately beneath the floor 4 upon slideways 8 fixed upon the partition floor 4 of the refrigerator by means of solder or the like.

The shutters 6 are so arranged as to have the perforations 7 thereof and the perforations 5 in registration when the shutter is in one position, and the openings 7 and 5 out of registration when the shutter is moved longitudinally a distance equal to the diameter of the openings 5 or 7.

Means for automatically moving the shutter 6 so that the perforations 5 and 7 are out of registration with one another when the doors 2 or 3 are opened, is provided in a plunger 10 projected through an opening 11 in the portion 12 of the wall 1 of the refrigerator. This plunger 10 has an upwardly extending portion 13 to which one end of the shutter 6 is secured as shown at 14. The outer end of the plunger 10 is provided with an arm 15 pivotally mounted on the plunger 10 intermediate the length of the arm by the provision of an L-shaped slot 16 through the arm which is arranged to engage with a pair of diametrically opposed pins, one of which is shown at 17. Obviously the arm 15 is hollow so as to admit the extreme outermost end of the plunger 10.

A compression spring 18 is disposed between the arm 15 and a stop plate 19 disposed at the rearward end of the opening 11 so that the plunger 10 is normally in the position shown in Figure 1, when the doors 2 and 3 are opened. At this time, the openings in the shutter 6 are out of registration with the openings in the floor 4.

A cavity 20 is provided in the outer surface of the portion 12 to entirely admit the arm 15 when the doors 2 or 3 are closed (see Figure 3). At this time, the plunger 10 will be forced inwardly against the action of the spring 18 and the perforations in the floor 4 of the shutter 6 will be in

registration with one another so that circulation of air from the ice compartment to the food compartment is assured. The arm 15 is provided with a roller 21 at each end thereof to reduce friction between the adjacent portion of the doors 2 or 3 and the arm 15 as the doors are closed.

From the foregoing description of the various parts of the device, the operation thereof may be readily understood. Let us assume that a refrigerator equipped with my improved shutter mechanism is inadvertently left with one of the doors 2 or 3 open. If the refrigerator were of the ordinary type, the cool air within the refrigerator which is normally circulating through the refrigerator would be free to flow downwardly, and warm air from the room in which the refrigerator is disposed would be free to enter, thereby causing loss of the cooling medium, and permitting the contents of the refrigerator to become warm. However, my present invention entirely precludes the possibility of such misadventure.

Let us assume that the door 2 has been left open. If this be the case, the shutter mechanism 6 will assume the position shown in Figure 2, and the openings 7 therethrough will be out of registration with the openings 5 in the floor 4, thus preventing circulation of the air from the cooling compartment to any other portion of the refrigerator. The arm 15 will be in the position shown in Figure 2 with the lowermost end within the cavity, but its outermost end in close engagement with the door 2, thereby permitting the plunger 10 to assume the position shown. This positioning of the plunger 10 is caused by the constant tendency to force the plunger outwardly brought about by the spring 18.

Let us assume that both of the doors 2 and 3 are left open. In this event, the mechanism will assume the position shown in Figure 1. Circulation will be stopped. If, however, both of the doors 2 and 3 are closed properly, then the arm 15 will lie entirely in the cavity 20 and the openings 5 and 7 in the floor and shutter 6 respectively will be in registration with one another and thereby permit efficient circulation of air and cooling medium through the refrigerator.

Obviously the floor 4 employed in my improved refrigerator construction may be a removable floor supported in any manner known in the art, and need not be fixed in the refrigerator. The removable floor greatly facilitates the cleaning of the refrigerator, yet does not hinder the efficient operation of my improved shutter mechanism.

I claim:

A refrigerator construction comprising two compartments separated by a perforated partition wall, a door for each compartment separated by a cross brace, a shutter slidably mounted in contact with and parallel to said partition wall, a plunger attached to the shutter, and actuating means for said plunger, housed, when the doors are closed, entirely within said cross brace, said actuating means being constructed so as to move said shutter out of registration with the perforations in said partition floor when one or both of said doors are open.

WILLIAM L. HUMMEL.
